United States Patent

Des. 236,172
Patented Aug. 5, 1975

236,172

LITERATURE HOLDER

Franklin G. Berlin, 2222 Avenue of the Stars,
Los Angeles, Calif. 90067

Filed July 16, 1973, Ser. No. 379,240

Term of patent 14 years

Int. Cl. D20—02

U.S. Cl. D6—25

FIG. 1.

FIG. 3.

FIG. 2.

FIG. 1 is a top plan view of a literature holder showing my new design.

FIG. 2 is a side elevational view thereof taken in the direction of the arrow 2 in FIG. 1.

FIG. 3 is a side elevational view thereof taken in the direction of the arrow 3 in FIG. 1.

I claim:

The ornamental design for a literature holder, substantially as shown.
